O. Wartemann Inventor:

UNITED STATES PATENT OFFICE.

OSKAR WARTEMANN, OF NEW YORK, N. Y., ASSIGNOR TO TRAUN RUBBER COMPANY
OF COLLEGE POINT, NEW YORK, A CORPORATION OF NEW JERSEY.

MOUTHPIECE FOR SMOKING-PIPES.

1,174,109.

Specification of Letters Patent. Patented Mar. 7, 1916.

Application filed July 1, 1915. Serial No. 37,475.

To all whom it may concern:

Be it known that I, OSKAR WARTEMANN, a citizen of the United States, and a resident of New York city, College Point, 5 borough of Queens, in the county of Queens and State of New York, have invented certain new and useful Improvements in Mouthpieces for Smoking-Pipes, of which the following is a specification.

10 This invention relates to improved mouth piece for smoking pipes.

The object of my invention is to provide a new and improved mouth piece for tobacco smoking pipes, which is strong, durable and 15 simple in construction.

In the accompanying drawings in which like letters of reference indicate like parts in all the figures: Figure 1 is a longitudinal section of my improved pipe stem or mouth 20 piece. Fig. 2 is an end view of the same. Fig. 3 is an end view of a stem that is circular in section.

The mouth piece 1 is made of hard rubber and is either circular in cross section 25 as shown in Fig. 3 or is oval or of a similar shape as shown in Fig. 2. At its inner end it is provided with a neck 2 which is of less diameter than the mouth piece and fits in the bore of a stem connected with the pipe 30 bowl in the usual manner. A shoulder or offset 3 is formed at the base of the neck 2. A groove 4 of about $\frac{1}{16}$ of an inch in 35 depth, more or less, is formed in the shoulder 3, one side of said groove 4 forming a continuation of the neck 2 so that the base of the neck is a short distance beyond the shoulder 3. The mouth piece 1 is provided with the usual bore 5 which also extends centrally through the neck 2. The mouth 40 pieces as usually formed are provided with a neck 2 which projects from the shoulder but does not extend inward beyond the shoulder as described above. Such necks break off very readily when the pipe is 45 seized by the mouth piece and the bowl tapped on a hard object for the purpose of knocking out the ashes and it is surprising how easily they break off. This has been a matter of great inconvenience and great 50 loss to the manufacturers of pipes.

My improved mouth piece does not break off even under the application of exceptionally great strength as evidenced by thousands of tests that have been made with my improved mouth piece provided with 55 the groove as described above and the ordinary mouth pieces.

It is immaterial what cross section the mouth piece has. The groove 4 is of the same shape as the outside of the neck and 60 one side of this groove is formed by the exterior of the neck.

The mouth piece may also be made of cel- 65 luloid, composition, bone or other suitable material.

Having described my invention what I claim as new and desire to secure by Letters Patent is:

1. A mouth piece for a tobacco pipe having at the inner end a neck of less diameter 70 than the body of the mouth piece, a groove being formed adjacent to the base end of said neck where it projects from the body of the mouth piece, said groove being formed in the shoulder at the junction of the body 75 and the neck, the inner wall of the groove being a continuation of the outer surface of the neck, substantially as set forth.

2. A mouth piece for tobacco pipes having at one end a neck of less diameter than 80 the body of the mouth piece, a shoulder formed adjacent to the base of said neck, a groove formed in the shoulder around the base of the neck, the inner wall of said groove being a continuation of the outer surface 85 of the neck, whereby the junction of the neck with the body is at a point a greater distance from the free end of the neck than the distance from the free end of the neck to the said shoulder, substantially as set 90 forth.

Signed at College Point in the county of Queens and State of New York this 29th day of June A. D. 1915.

OSKAR WARTEMANN.
